FIG. 1

FIG. 2

FIG. 3

FIG. 4

FIG. 5

FIGURE 1 is a front perspective view of an industrial tractor embodying my new design;

FIGURE 2 is a perspective view thereof showing the front and side opposite that shown in FIGURE 1;

FIGURE 3 is a side elevational view thereof taken on a reduced scale;

FIGURE 4 is a rear perspective view thereof; and

FIGURE 5 is an enlarged top plan view thereof.

Portions of the elements shown in broken lines in FIGURE 1 have been omitted from the remaining views for clarity of illustration.

The dominant features of my design reside in the portions illustrated in solid lines.

I claim:

The ornamental design for an industrial tractor, as shown and described.
